UNITED STATES PATENT OFFICE

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed November 17, 1930, Serial No. 496,130. Renewed October 2, 1931.

My invention relates to railway traffic controlling apparatus for utilizing coded current in track circuits and in line circuits for the control of either or both wayside and cab signals and more particularly, it relates to apparatus for utilizing coded current in the running rails and in line circuits for the control of an absolute permissive block signaling system.

I will describe one form of apparatus embodying my invention and will then point out the novel features thereof in claims.

The accompanying Figures 1^a, 1^b, 1^c and 1^d when placed end to end in the order named with Fig. 1^a on the left, form a diagrammatic view showing one form of apparatus embodying my invention when applied to a stretch of single track railway that includes a passing siding designated in the drawings by the reference character PS. In describing my invention, I shall assume the left-hand end of each figure to be west and the right-hand end to be east and I shall speak of a train traveling from the right to the left as a westbound train and one traveling from the left to the right as an eastbound train. Also, at certain points in the description I shall refer to the apparatus shown in Fig. 1^a as being associated with the track section to the left of location A of Fig. 1^a. In the following description, reference is made to the accompanying figures wherein like characters of reference designate corresponding parts: the numeral 1 being prefixed to the reference character when the part is associated with westbound traffic and the numeral 2 being prefixed to the reference character when the part is associated with eastbound traffic. Also an exponent is added to the reference character to designate the location of the part.

The traffic rails 1 and 2 are arranged in track sections D—A, A—B, B—C and C—D by the usual insulated rail joints 3. It will be understood that other arrangements of track sections other than that herein disclosed may be employed without departing from the spirit and scope of my invention.

Energy for the operation of the apparatus is supplied by the line transformer L, one of

which is located at each junction of adjacent track sections. The primary 4 of each line transformer is connected to the transmission line E which is constantly supplied with alternating current of any convenient commercial frequency such as 60 cycles per second from a source not shown in the drawings. 55

At each junction of adjacent track sections, there is provided an auxiliary transformer M, the primary 5 of which is constantly supplied with current from the secondary 6 of the associated line transformer L. The secondary 7 of each auxiliary transformer M is connected to the input terminals of a rectifier N. The rectifier N supplies direct current for the operation of certain parts of the apparatus. 60

A coded transmitter CT is located at each junction of adjacent track sections and its motor element 8 is supplied with current from the associated rectifier N by the wires B1 and C1. This code transmitter is to be of any of the standard types commonly used in code systems and as here shown it will be understood that the upper contact 9 periodically closes its contact at a rate taken in this description to be 180 times per minute, and that the lower contact 10 closes its contact at the rate here taken as 80 times per minute, although any other rates of interruption 75 could equally as well be employed. 80

Each track section is provided with a track circuit which includes a code feeding track transformer T and a code following track relay TR located at each end of the track section. The alternating current supplied to the rails by each track transformer T is constantly coded or periodically interrupted at the rate of 80 or 180 cycles per minute, or any other code frequency desired, and the coded alternating current is utilized to operate the code following track relays for controlling wayside signals. Furthermore this coded alternating current is adaptable to control train carried devices for governing 85 the operation of cab signals where such train carried devices are controlled by power received inductively from the running rails such for example as that disclosed and claimed in Letters Patent of the United 90 95 100

States, No. 1,773,472 filed by P. N. Bossart on the 7th day of February, 1927.

The general arrangement of all track circuits is the same. A detailed description of the track circuit for the section C—D is submitted as being typical of all track circuits except for certain modifications at staggered opposing intermediate signals to be pointed out as the description progresses. The track transformer 2T^D has its secondary 11 connected across the rails 1 and 2 at the east end of the section C—D through the current limiting reactor 12. The second transformer 1T^C has its secondary 13 connected across the rails 1 and 2 at the west end of the section through the current limiting reactor 14. The primary 21 of transformer 2T^D is supplied with coded energy by a circuit that includes the following elements: secondary 6 of line transformer L^P, wire BX110, the 180 code contact 9 of code transmitter CT^D, wire 22, a circuit controller 23 operated by the mechanism of a wayside signal 2S^D as indicated by a dotted line and which is closed when the signal occupies either its approach or proceed position, wire 24, a normally closed back contact 25 of a line relay 1F^D to be later described, primary 21 and the common wire CX110 to the common terminal of the secondary 6. In the event signal 2S^D occupies a stop position, the coded alternating current is supplied to the primary 21 from the secondary 6 by wire BX110, 80 code contact 10 of code transmitter CT^D, wire 26, controller 23, and then by the same circuit as traced above. The primary 27 of the track transformer 1T^C located at the west end of the section C—D is supplied with 180 code energy by a circuit from the secondary 6 of the line transformer L^C, wire BX110, 180 code contact 9 of code transmitter CT^C, wire 28, circuit controller 29 operated by the mechanism of the signal 1S^C and closed when the signal occupies either the proceed or approach position, wire 30, front contact 31 of a line relay 2F^C when energized in a manner to be later pointed out, primary 27 and wire CX110 to the common terminal of the secondary 6 of L^C. The primary 27 is supplied with 80 code alternating current by the path from wire BX110 through the 80 code contact 10 of code transmitter CT^C, wire 32, controller 29 with signal 1S^C in the stop position and then as before traced. It is to be noted that normally 180 code alternating current is supplied to the rails of the section C—D by the secondary 11 of the track transformer 2T^D located at the east end of the section, while the track transformer 1T^C located at the west end of the section is normally ineffective to supply current to the rails inasmuch as its primary circuit is opened at the contact 31 of a line relay 2F^C.

All track relays of my invention are preferably two element relays each having one ele-

ment constantly supplied with non-coded alternating current and a second element supplied with coded current from the track circuit. The track relay 1TR^D located at the east end of the section C—D has its element 15 constantly energized by alternating current supplied from the secondary 6 of the transformer L^P over the wires BX110 and CX110. The second element 16 is then connected across the rails 1 and 2 through the resistor 17. The second track relay 2TR^C for the section C—D has its element 15 constantly supplied with alternating current from the secondary 6 of the line transformer L^C, while its second element 16 is connected across the rails 1 and 2 through the resistor 18. It is to be observed that the resistor 17 is shunted whenever the line relay 1F^D is energized closing its front contact 19 and that the resistor 18 is normally shunted by a path that includes the back contact 20 of the line relay 2F^C. These track relays are designed to be responsive to alternating current code impulses. It follows then that when the track section C—D is unoccupied both track relays 1TR^D and 2TR^C are operated at the rate of 180 or 80 cycles per minute by coded alternating current supplied to the rails by either one or the other of the track transformers 1T^C or 2T^D depending upon the direction of traffic as will be brought out later in the specifications but normally they are operated by 180 code supplied by the transformer 2T^D located at the east end of the section.

Each track relay of the section C—D controls decoding apparatus which includes two decoding transformers designated by the reference characters X and Y together with three decoding relays designated P, HP and TP. Looking at track relay 2TR^C of location C for example, the primary 33 of the decoding transformer 2X^C is supplied with direct current from the rectifier N^C through the armature 34 of the track relay 2TR^C. When relay 2TR^C is energized current flows from the positive terminal of the rectifier N^C along wire B1, armature 34 in engagement with its front contact, the right-hand half of the primary 33 of transformer 2X^C to a center tap and by wire C1 to the negative terminal of rectifier N^C. When the track relay 2TR^C is deenergized and armature 34 down in engagement with its back contact, the current flows from the rectifier N^C through the left-hand half of the primary 33. The primary 35 of the decoded transformer 2Y^C is supplied also with direct current, when the relay 2TR^C is energized and armature 34 raised, by a circuit that passes through the back contact 36 of the line relay 2F^C, the left-hand half of the primary 35 to a center tap and then by wire C1 to the negative terminal of rectifier N^C. When relay 2TR^C is deenergized and armature 34 down, the right-hand half of the primary 35 receives current through the back

contact 37 of the line relay 2F^c. It follows that with the track relay 2TR^c operated by a coded alternating current and its armature 34 alternately in engagement with its front and back contact, that an alternating voltage is induced in the secondary 38 of the decoding transformer 2X^c, the frequency of which is the same as the frequency of operation of the track relay and that whenever the track relay ceases to operate no voltage is induced in the secondary 38. Likewise with relay 2TR^c operated by coded alternating current an alternating voltage is induced in the secondary 39 of the decoded transformer 2Y^c as long as the line relay 2F^c is down. The secondary 38 is connected to the input terminals of a rectifier 40 to whose output terminals the decoding relay 2TP^c is connected. A portion of the secondary 39 of the decoding transformer 2Y^c is connected to the input terminals of a rectifier 41 to whose output terminals the decoded relay 2HP^c is connected. Both of these secondary circuits being non-tuned, it follows that with the track relay 2TR^c alternately energized and deenergized in step with either 180 code or 80 code, both the decoding relays 2TP^c and 2HP^c are steadily energized and that when relay 2TR^c ceases to operate on code these decoded relays are deenergized. Across the terminals of secondary 39 is connected the reactor 42 and a portion of the reactor 42 is connected to the input terminals of the rectifier 43 in series with a condenser 44. The decoding relay 2P^c is connected to the output terminals of the rectifier 43 and the parts are so chosen that this decoding relay 2P^c is responsive only to the 180 code. Thus under conditions when 180 code current is supplied to the rails, all three of the decoding relays associated with the track relay 2TR^c are energized while under conditions when 80 code current flows in the rails, the decoding relays 2TP^c and 2HP^c are energized, and the relay 2P^c is deenergized. When the relay 2TR^c ceases to operate on code the decoding relays are all deenergized. Furthermore, it will be noted that the energizing of the decoding relays 2P^c and 2HP^c is controlled by the line relay 2F^c.

50 The track relay 1TR^p located at the east end of the section C—D will also be operated by the 180 code alternating current normally supplied to the rails by the transformer 2T^p located at the same end of the section. With the armature 34 of relay 1TR^p being operated on 180 code, the decoding relay 1TP^p will be energized in the same manner as the decoding relay 2TP^c associated with the relay 2TR^c and described above. However, under normal conditions the decoding relays 1P^p and 1HP^p also associated with the track relay 1TR^p at times are not normally energized by the operation of the track relay 1TR^p, due to the fact that the circuit through the decoding transformer 1Y^p from the arma-

ture 34 of relay 1TR^p is open at the front contacts 77 and 78 of a line relay 1F^p. Thus at a time when the track relay 1TR^p is being operated by a coded current from the track transformer 2T^p, it controls only the one decoded relay 1TP^p.

It is to be noted that the code following track relays 1TR^A and 2TR^B located at intermediate locations A and B respectively are each provided with a second armature 45, the purpose of which will now be described. The primary 21 of the track transformer 2T^B is supplied with energy from the secondary 6 of the line transformer L^B over wire BX110, the 45 armature of the code following track relay 2TR^B of the section B—C, front contact 110 of the line relay 2F^B, wire 111, back contact 112 of a relay 1V^B to be referred to later, front contact 113 of line relay 1F^B, primary 21 and wire CX110 to the common terminal of the secondary 6. It follows that with the code following track relay 2TR^B being operated by 180 code alternating current supplied by the track circuit for the section B—C, then 180 code energy is also supplied to the track circuit of the section A—B. In other words, the code of the section B—C is passed on to the track section A—B and the location B, at which only a westbound signal is located acts as a cut section location for eastbound traffic. Likewise at location A, at which only an eastbound signal is located, the primary 21 of the track transformer 1T^A is supplied with energy from the secondary 6 of the line transformer L^A over wire BX110, the 45 armature of the code following track relay 1TR^A, back contact 114 of the line relay 1F^A, wire 115, back contact 116 of relay 2V^A, back contact 117 of line relay 2F^A, primary 21 and wire CX110 back to the secondary 6. Thus when the line control circuits of relays 1F^A and 2F^A are set in a manner to be shortly described, to render track transformer 1T^A effective, the code of the section to the left of location A is passed on to the section A—B and the location A acts as a cut section for eastbound traffic. As a matter of fact with my invention a cut section may readily be located at any point in any track section with practically no complications, a line relay being provided to determine the direction in which the track circuits are to operate in the same manner as will be shortly pointed out for all track circuits of my invention. Once the direction of traffic is determined the code of the section in advance, for the direction selected, is passed on to the section in the rear of the cut section by the code following track relay in a manner similar to that whereby the code following track relays 1TR^A and 2TR^B pass on the code at which they operate. With a train shunting the track relay at a cut section location so that the relay ceases to operate on code then the track circuit for the rear section is without coded energy.

To sum it up thus far, coded alternating current is normally supplied to the rails at the east end of each section. The code following track relay located at the west end of the section is effective to control the operation of the eastbound signal. The code following track relay connected to the rails at the east end of the section normally acts as only to control a line circuit. The track transformer located at the west end of the section is normally ineffective to supply current to the rails. At locations acting as a cut section for either or both directions of traffic the code of the track circuit of the section in advance is repeated by the code following track relay in the track circuit for the section in the rear.

Each track section is provided with a line control circuit that includes a line relay located at each end of the section and designated by the reference character F. Taking section A—B for example, the line circuit extends from the positive terminal of the rectifier N^B, wire B1, wire 46, front contact 47 of decoding relay 1TP^B, wire 48, front contact 49 of the line relay 2F^B of the section B—C, wire 50, front contact 51 of the decoding relay 2TP^B, wire 52, winding of relay 1F^B, line wire 153, winding of relay 2F^A, wire 54, front contact 55 of the decoding relay 2TP^A, wire C1, common line wire 56 and the wire C1 at location B to the negative terminal of the rectifier N^B. A by-pass is provided around the front contact 55 of the relay 2TP^A which includes the wire 57, front contact 58 of the relay 2V^A and wire 59 to the common wire C1. Also a by-pass is provided around the front contact 49 of the relay 2F^B and the front contact 51 of the decoding relay 2TP^B which by-pass includes a wire 60 branching from wire 48, front contact 61 of relay 2V^B and wire 62 to the wire 52. This line circuit for section A—B being normally closed, and the two line relays 2F^A and 1F^B connected in series in the circuit the relays are both normally energized. Each track section is provided with a similar line control circuit. However, the line circuit for all track sections at siding locations such as section C—D is normally open and its line relays normally deenergized.

At each westbound signal location, there is provided a code following line relay LR similar in design to the code following track relays of my system. Taking for example, the code following line relay LR^C, the element 63 is constantly supplied with non-coded alternating current from the secondary 6 of the line transformer L^C. The element 64 is supplied with coded alternating current by the following line circuit: secondary 6 of the line transformer L^B, wire BX110, 180 code contact 9 of the code transmitter CT^B, wire 65, circuit controllers 66 and 67 both of which are operated by the signal 1S^B and closed with the signal at proceed or approach,

wire 68, front contact 69 of the line relay 2F^B, wire 70, front contact 71 of decoding relay 2TP^B, line wire 72, contact 73 of line relay 1F^C, wire 74, contact 75 of decoding relay 1TP^C, element 64, wires CX110 and C1, common line wire 56 and wires C1 and CX110 at the location B to the common terminal of the secondary 6 of the transformer L^B. It is to be seen therefore that normally the code following line relay LR^C is operated on 180 code and its armature 76 therefore alternately making contact with its front and back contacts at a rate of 180 times a minute. The code following line relay LR^C normally controls the decoding relays 1P^C and 1HP^C. With relay LR^C operated on code then direct current flows from the positive terminal of the rectifier N^C through armature 76, wire 79, front contact 80 of relay 1F^C, the right-hand half of the primary 35 of the decoding transformer 1Y^C and back to the negative terminal of rectifier N^C. With line relay LR^C deenergized, then the left-hand half of the primary 35 is energized by current that flows through the back contact of 76, wire 81, front contact 82 of relay 1F^C, the left-hand half of primary 35 and to the negative terminal of rectifier N^C. The operation of the decoding transformer 1Y^C and its associated circuits is identically the same as that described for the decoding transformer 2Y^C and its associated circuits. Under traffic conditions that deenergize the line control relay 1F^C, the primary 35 of the decoding transformer 1Y^C is disconnected from the front and back contacts of the armature 76 of relay LR^C and is connected to the front and back contacts of the armature 34 of the track relay 1TR^C by the back contacts 83 and 84 of the line relay 1F^C. At eastbound signal locations such as location A, the code line circuit for the opposing westbound signal 1S^D is carried through the several relays. To be specific, the circuit for element 64 of code following line relay LR^B is along wire 103, front contact 104 of the decoding relay 2TP^A, front contact 105 of line relay 2F^A, wire 106, front contact 107 of the decoding relay 1TP^A, front contact 108 of the line relay 1F^A, line wire 109 and then through the code transmitter and to the secondary of the line transformer at the next location to the left of location A, such for instance as location D, in a manner similar to that described for the code line relay LR^C at the location B.

At the junction of adjacent intermediate track sections and at the east end of the passing siding there is provided directional stick relays commonly used in absolute permissive block systems and here designated by the reference character V with proper exponents. These stick relays perform similar functions as that of the directional stick relays used in standard A. P. B. systems—that

is, to establish directional control and to provide for following train movements. As the circuits for selecting these directional relays are similar for all directional relays, it is deemed sufficient to describe but one in detail for an understanding of all. Taking relay $1V^B$ for example, this relay has a pick-up circuit as follows: positive terminal of rectifier N^B , wire 183, back contact 184 of the opposing stick relay $2V^B$, wire 85, back contact 86 of the decoding relay $2HP^B$, wire 87, back contact 89, back contact 90, front contact 91 of the decoding relay $1HP^B$, winding of relay $1V^B$, wire 92 and the common return wire 56 to the negative terminal of the rectifier N^B . The stick circuit for this relay $1V^B$ consists of the positive wire $B1$, wires 46 and 93, back contact 94, front contact 96, winding of relay $1V^B$ and to common as before.

Each track section is provided with wayside signals to govern traffic in opposite directions through the section and designated by the reference character S with proper exponents. These wayside signals may be of any of the standard types, but are here shown as three position semaphore signals. The operating circuits are controlled by the associated decoding relays and as the circuits of all signals are alike, a description of any one may be sufficient for the understanding of all. Referring to signal $1S^B$, the proceed operating circuit extends from one terminal of the secondary 6 of the line transformer L^B along wire $BX110$, wire 97, front contact 98 of decoding relay $1HP^B$, wire 99, front contact 100 of the decoding relay $1P^B$, wire 101, signal mechanism of $1S^B$ and common wire $CX110$ to the common terminal of the secondary 6. The approach operating circuit branches from wire 99 and extends along wire 102, signal mechanism $1S^B$ and to the common wire $CX110$. While signals for displaying only proceed, approach and stop are disclosed, it is obvious that signals displaying additional indications can be used if desired by providing additional apparatus for delivering additional codes under proper traffic conditions.

Having pointed out the different circuits and apparatus with which my invention is provided I shall now describe the operation and I shall first assume that all track sections are unoccupied. As previously pointed out the track rails of each section are supplied with 180 code energy by the track transformer $2T$ located at the east end of the section and this coded track current operates each of the track relays of the section. The operation of the track relay located at the west end of the section on 180 code effects the energization of all three of the associated decoding relays of which the $2P$ and the $2HP$ relays jointly control the operation of the eastbound signal. The track

relay located at the east end of the section acts normally as a floater and normally is effective to energize only the $1TP$ decoding relay. The $1TP$ and the $2TP$ decoding relay days of each section act to control the code line circuit and the line control circuit for the section, the latter of which is normally energized for all intermediate sections and deenergized at all siding locations. 180 code current being supplied normally to the code line circuit, the code following line relay is normally operated thereby and thus effects energization of the $1P$ and $1HP$ decoding relays which relays in turn govern the operation of the westbound signal of the section. Therefore, coded alternating current is normally supplied at the east end of each section to govern the eastbound signal and to establish coded alternating current in the code line circuit which governs the operation of the westbound signal. With coded alternating current thus supplied at the east end of the section, the apparatus is normally set to control train carried devices for an eastbound train, where such devices are those described and disclosed in the United States Letters Patent, No. 1,773,472, heretofore mentioned.

Assuming next that an eastbound train is approaching the location A having passed a passing siding to the left of Fig. 1^a at the east end of which passing siding the apparatus is the same as that disclosed at the location D of Fig. 1^a. The train by entering the first section east of this siding, which may be the section to the left of location A, or there may be several intermediate sections, but assuming it is the section to the left of A, would shunt the track relay located at the west end of the section to the left of A and thereby open the line control circuit for its F relays. This line circuit being opened at a front contact similar to contact 118 of the decoding relay $2TP^D$. However, this line circuit will be at once reclosed at a front contact similar to contact 119 of the directional stick relay $2V^D$ and thus the line control circuit for the section to the left of A remains energized as the eastbound train occupies the section. It follows then that the track circuits for each successive section up to the passing siding PS remain normal—that is, set for eastbound traffic. The deenergizing of the $2TP$ decoding relay (not shown) for the section to the left of location A, will open the code line circuit of the code following line relay LR^B setting the westbound signal $1S^B$ at stop. Signal $1S^B$ assuming a stop position, the code line circuit for the next westbound signal is opened at its controller 67 and this will set the next westbound signal at stop, and in turn each successive westbound signal to the passing siding PS will be set at stop. Signal $1S^C$ at the west end of siding PS on being set at stop permits 80 code alternating current to be

supplied to the code line circuit through the stop position of its controller 29. This 80 code alternating current operating line relay LR^P energizes the decoding relay 1HP^D only 5 and causes the westbound signal 1S^D to display an approach signal. It follows that the westbound signal to the rear of the signal 1S^D will remain normal displaying a proceed signal. The code feeding transformer 2T^A being 10 active, the train carried devices are influenced by 180 code as the train travels the track section on the left of A. As the train approaches the location A, the floater track relay 1TR^A will eventually be shunted and cease to operate on code with the result that the decoding relay 1TP^A becomes deenergized and the line 15 control circuit for relay 1F^A will be cut off from energy at contact 123. However, the line circuit for 1F^A is transferred to the code line wire 109 by a back contact 124 and this line wire 109 is connected to positive power at the west end of the section (see location D for illustration), through a back contact 125 of the 2TP decoding relay and a front contact 20 126 of the directional relay 2V^D therefore the line control circuit for relay 1F^A is retained energized and the transformer 2T^A remains active to supply 180 code as the train travels the full length of the section. 25

30 The train upon passing signal 2S^A shunts the track relay 2TR^A and its associated decoding relays 2TP^A, 2HP^A and 2P^A are all de-energized setting the signal 2S^A at stop. The directional stick relay 2V^A is energized by its 35 pick-up circuit in the usual manner and is retained picked up by its stick circuit. Relay 2F^A being up, the line control circuit for the section A-B whose connection to common has been opened at the front contact 55 of relay 40 2TP^A is now closed at the front contact 58 of the directional relay 2V^A. Also the control line circuit for the section to the left of A although cut off from power at the contact 120 of relay 2TP^A is again closed at the front contact 45 121 of the stick relay 2V^A leaving the section to the rear of location still set for eastbound traffic. The code line circuit for the westbound signal 1S^B is now opened at the contact 104 of relay 2TP^A assuring thereby 50 that the opposing westbound signals remain in a stop position. Signal 2S^A being set at stop, 80 code is now supplied to the track section to the left of location A by the track transformer 2T^A through the stop position of the controller 128 and the front contact 129 of the directional relay 2V^A, and thus as soon 55 as the train vacates the section to the left of A, the eastbound signal to the rear of signal 2S^A is operated to indicate an approach indication. The track transformer 2T^B is retained effective to supply 180 code to the rails of section A-B during the time the train travels the full length of the section A-B in the same manner as described for the section 60 to the left of the location A and the 180

code is effective to control the train carried cab signals.

The eastbound train on entering section B-C shunts track relay 2TR^B and its associated decoding relays are thereby deenergized and the directional stick relay 2V^B picked up in the usual manner. The code line circuit for relay LR^C is now open at contact 71 of the decoding relay 2TP^B to still retain the opposing westbound signals at 75 stop. The line control circuit for the section B-C remains energized in the same manner as described for the line circuit of section A-B as the train entered that section. That is, this line circuit is now cut to power through the front contact 122 of relay 2V^B and the track transformer 2T^C remains effective to supply coded current to the traffic rails to insure control of the cab signals as the train travels the section B-C. The track relay 2TR^B ceasing to operate on code while the train occupies the section B-C, no code is 80 supplied to the track circuit of the section A-B with the result that the eastbound signal 2S^A is held at stop during occupancy of 85 section B-C by the eastbound train.

As the train passes the signal 2S^C, it shunts the track relay 2TR^C causing thereby the eastbound signal 2S^C to assume the stop position. The code line relay LR^P which had 90 been operated on 80 code as the train was approaching the passing siding PS is now cut off from energy at the front contact 134 of the decoding relay 2TP^C and thus the westbound signal 1S^D now assumes the stop position and the code line circuit to the east of signal 1S^D is now fed 80 code and the first westbound signal to the rear of 1S^D caused to display an approach signal. The line control circuit for section C-D remaining de-energized, the track transformer 2T^D remains active to supply code to the track relays of the section to insure proper control of the cab signals as the eastbound train travels the section C-D. As the train vacates the section B-C, 80 code is supplied by the track transformer 2T^C which operates the track relay 2TR^B on 80 code and the track transformer 2T^B supplies 80 code to the section A-B and thus signal 2S^A assumes the approach 100 position. The line control circuit to the west of location C being restored to normal as the train vacates section B-C, the code line circuits are reenergized with 180 code and all westbound signals to the west of the location C are again cleared. 105

In the event signal 2S^D had been set at stop by some westbound train approaching the siding PS, the signal 2S^C would have displayed an approach signal to the eastbound train and the transformer 2T^D would supply 110 80 code to the rails to effect the cab signals on 80 code as the train travels the section C-D.

Assuming a second eastbound train enters 115

the section to the west of location A while the first eastbound train occupied either section A—B or B—C. The 80 code current fed to the rails by the track transformer 2T^A provides proper control of the cab signals of this following eastbound train. In the case the second eastbound train passes the stop signal 2S^A and enters section A—B while the first train occupied the section B—C, no coded track circuit current being supplied to the rails by the transformer 2T^B, the cab signals will be without control and will indicate an occupied block.

Next let us assume a westbound train occupies section C—D and that the signal 1S^D displays a stop signal as the result. As the westbound train enters the section C—D from the east and shunts both track relays 1TR^D and 2TR^C, the directional stick relay 1V^D is picked up. The stick relay 1V^D being picked up the line control circuit for the section C—D is connected to positive power at the front contact 127 and thereby the line relays 1F^D and 2F^C are energized. Line relay 1F^D up opens the circuit to the primary 21 of transformer 2T^D and this track transformer then becomes inactive. Line relay 2F^C up closes the circuit to primary 27 of the track transformer 1T^C which now becomes active to supply code energy to the rails of C—D. Furthermore, the energization of relay 1F^D transfers the control of the decoding relays 1P^D and 1HP^D from the code line relay LRD to the code track relay 1TR^D while with relay 2F^C up the circuit to the decoding transformer 2Y^C is open and the eastbound signal 2S^C set at stop. With signal 2S^C at stop, 80 code is then supplied by the track transformer 2T^C to the rails of the section B—C and in turn by the track relay 2TR^B to the track transformer 2T^B of the section A—B and the eastbound signal 2S^A caused to assume the approach position. As the rear of the westbound train passed signal 2S^D, the 80 code fed to the track by transformer 1T^D operates relay 2TR^D to reenergize the decoding relay 2TP^D which in turn energizes the line relay 2F^D, with the result that the track circuit east of D is transferred to the normal eastbound direction and the signal 2S^D cleared. With coded alternating current supplied to the rails of the section C—D by the track transformer 1T^C, it is obvious that the train carried devices of this westbound train are under control of the track circuit. As the westbound train advances and enters the section B—C, the shunting of the track relays 1TR^C and 2TR^B to deenergize the line control circuit transfers the supply of coded track current from the transformer 2T^C to the transformer 1T^B. The line control circuit for line relays 1F^C and 2F^B being now open and these relays deenergized the line control circuit for the section A—B is opened at the contact 49 of

relay 2F^B and the supply of the coded track current for the section A—B transferred from transformer 2T^B to the transformer 1T^A. This transfer of the supply of track circuit current from the source at the east end to the source at the west end of the section will be repeated for each successive sections up to the next passing siding. As the F relays of each section become deenergized, they also transfer the control of the 1P and the 1HP decoding relays from the code following line relay LR to the code following track relay 1TR of the respective track section. All the westbound signals up to the next passing siding are now therefore directly controlled by the coded track circuit for this westbound train in the same manner as the eastbound signals were controlled by the coded track circuit for the eastbound train. Inasmuch as the deenergizing of the F line relays left the 2P and the 2HP decoding relays without control, all the opposing eastbound signals are set at stop as the westbound train enters this stretch of single track.

As the rear of the train passes the signal 2S^C, the 80 code fed to the track by transformer 1T^C operates relay 1TR^D and in turn the decoding relay 1HP^D is energized. The energizing of relay 1HP^D opens the holding circuit for the stick relay 1V^D and with the stick relay 1V^D down, the 2F^C and 1F^D relays are again deenergized. Deenergizing 2F^C and 1F^D transfers the control of the track circuit back to the transformer 2T^D and thus the apparatus for the section C—D is restored to its normal condition. However, the signal 1S^D is caused to display an approach indication as the result of 80 code fed to the code line relay LRD through the stop position of the controller 29 of the signal 1S^C. It is obvious that as the westbound train passed the signal 1S^C, it is necessary for all F relays of the section B—C to open in order that code current may be fed to the rails to effect the cab signal. This requirement insures that the F relays to the west of signal 2H^A are in turn deenergized to set their respective eastbound signals at stop. This operation provides a more reliable check on the setting at stop of the opposing signals than is now obtained in the present day absolute permissive block systems.

As the westbound train enters section A—B and shunts the now active relay 1TR^B, its associated decoded relays 1P^B, 1HP^B, and 1TP^B are concurrently deenergized with the result that the westbound signal 1S^B assumes the stop position. The directional stick relay 1V^B is now picked up and retained energized in the usual manner. With the stick relay 1V^B up, the line control circuit for the section B—C is retained open at the back contact 130 to thereby retain the track circuit for the section B—C set for westbound traffic. The line control circuit for the section A—B

is now held open at contact 47 of the relay 1TP^B and thus the opposing eastbound signals are retained at stop. With the train vacating section B—C, the 80 code track current of the circuit is now supplied to the section by the transformer 1T^B establishing an approach indication at signal 1S^C. This circuit for 1T^B may be traced from the secondary 6 of line transformer L^B along wire 10 BX110, 80 code contact 10 of CT^B, controller 66 in stop position, contact 131 of relay 1V^B, wire 132, wire 68, back contact 133, primary 27, and wire CX110 to the common terminal of 6. As the line control circuit to the relays 15 1F^B and 1F^C is retained open at the back contact 130 of the directional relay 1V^B, these relays remain deenergized whereby the apparatus for the section B—C remains set for westbound traffic. The westbound train as 20 it travels the section A—B has its cab signals controlled by 180 code fed to the rails by the track transformer 1T^A inasmuch as the track relay 1TR^A is operated by 180 code and this relay repeats the code by its armature 45. 25 Assume a second westbound train advances past the signal 1S^C during the time the first train occupies the section to the west of location A. The signal 1S^C displays approach and the 80 code supplied to the track circuit 30 by transformer 1T^B located at the west end of the section influences the cab signals on this following train. Should the second train advance past the signal 1S^B while the first train occupies the section to the left of A, the signal 1S^B displays a stop signal and the absence of coded current in the rails of 35 the section A—B leaves the cab signal without control. That is to say, the location A acts as a cut section for westbound traffic. Let us now assume that there is no following 40 westbound train and that the first westbound train advances west through the stretch of single track to the next passing siding at the east end of which the apparatus will be similar to that shown at location D of Fig. 1^d and which I shall use to describe the operation. As the rear of the westbound train passes 45 the location D, the track transformer 1T^P supplies 80 code to the track circuit and this 50 80 code operates the track relay 2TR^D which when so operated energizes the decoding relay 2TP^D. The 80 code energy also operates the track relay located at the east end of the section and the operation of this track relay 55 on code energizes its 1T^P decoding relay. The energizing of the 2TP^D and the 1T^P relays of the section will close the line control circuit for the line relay 2F^D and its companion relay located at the east end of the section. The energizing of these line relays acts 60 to disconnect the track transformer 1T^D and render active the track transformer located at the east end of the section. As soon as the track relay at the east end of the section becomes active, the normal circuits for the sec-

tion are restored and the eastbound signal 2S^P is cleared. Also the energizing of the line relays will deenergize the westbound directional relay and thus act to reenergize the line control circuit for the next section to the 70 east. The restoring of its line control circuit will act to restore the circuits of this section to their normal condition and, in like manner, all the line circuits of each successive track section of the stretch of single track 75 will be restored and the eastbound signals cleared, and the westbound signals again under the control of the coded line circuit.

To sum up, the apparatus of my invention provides normal coded track circuit control 80 for the signals governing movements through the stretch of single track in one direction (eastward in the figures) and normal coded line circuit control for the opposing signal (westward). For an eastbound movement these normal track circuits provide control 85 of the eastbound wayside signals and coded energy for the control of cab signals and train control devices, and deprive all westbound wayside signals of coded line circuit control setting them at stop and leaves the cab signals of a westbound train without coded energy. The apparatus also provides means controlled by a westbound movement for 90 causing all westbound wayside signals and the cab signals of the westbound train to be controlled by continuous coded track circuits which leave the eastward wayside signals without any control setting them at stop 95 and which also deprives eastward trains of 100 cab signal code.

Such a system as here provided is practically immune from foreign code and from 105 propulsion current as far as the track circuits are concerned. The code line circuit insures a system free from inductive interference by commercial transmission lines. Such a system is adaptable to either wayside signals or cab signals, or both. Furthermore, such a system provides a more reliable check 110 on the protection of head-on movements than is obtained in present day A. P. B. systems.

Although I have herein shown and described only one form of apparatus embodying my invention, it is understood that various changes and modifications may be made therein within the scope of the appended 115 claims without departing from the spirit and scope of my invention.

Having thus described my invention, what 120 I claim is:

1. In combination, a track section, a signal located at each end of the section to govern traffic in opposite directions through the section and each adapted to display several distinctive indications, a source of current located at each end of the section each adapted to supply current of different characteristics to the traffic rails, a track relay at each end 125 of the section each permanently connected to 130

the traffic rails and responsive to the different characteristics of the current supplied to the rails to selectively govern the several indications of the signal located at its respective end of the section, and means responsive to the direction of traffic to selectively render one or the other of said sources effective to supply current to the rails and to render the track relay at the same end as the effective 10 source of current ineffective to select the several indications of its respective signal.

2. In combination, a track section, a signal located at each end of the section to govern traffic in opposite directions through the section 15 and each adapted to display several distinctive indications, a source of current located at each end of the section each adapted to supply alternating current of different codes to the traffic rails, a track relay at each 20 end of the section each permanently connected to the rails and responsive to coded alternating current, a plurality of decoding relays associated with each track relay to selectively govern the several indications of the 25 signal located at the same end of the section, means to selectively energize the decoding relays in accordance with the code operating the associated track relay, and means responsive to the direction of traffic to selectively render one or the other of said sources effective 30 to supply current to the rails and to render the track relay at the same end as the effective source of current ineffective to energize the associated decoding relays.

3. In combination, a stretch of traffic rails over which traffic may move in either direction, a signal to govern traffic through the stretch, a decoding relay to govern the operation of the signal, a code following track relay and a code following line relay associated with the decoding relay and each of which is responsive to coded current, a current source adapted to supply coded current to said track relay and to said line relay, and directional means to place the decoding relay under the control of the track relay or under the control of the line relay according to the direction of traffic.

4. In combination, a stretch of traffic rails over which traffic may move in either direction, a signal having several distinctive indications to govern traffic through the stretch, a plurality of decoding relays to selectively govern the several indications of the signal, a code following track relay and a code following line relay associated with said decoding relays, decoding means to selectively energize the decoding relays according to the code operating the associated track relay or line relay, a current source adapted to supply coded current of different codes to said track relay and to said line relay, directional means to place the decoding means under the control of either the track relay or the line relay according to the direction of traffic, and circuit

means to select the different codes in accordance with traffic conditions in advance of the signal.

5. In combination, a stretch of traffic rails over which traffic may move in either direction, a signal having several distinctive indications to govern traffic through the stretch, a plurality of decoding relays to selectively govern the several indications of the signal, a code following track relay and a code following line relay associated with the decoding relays and each responsive to code impulses of alternating current, decoding means to selectively energize the decoding relays according to the code operating the associated track relay or line relay, a current source adapted to supply coded alternating current of different codes to said track relay and said line relay, directional means to place the decoding means under the control of either the track relay or the line relay according to the direction of traffic, and circuit means to select the different codes in accordance with traffic conditions in advance of the signal.

6. In combination, a stretch of traffic rails over which traffic may move in either direction, a signal to govern traffic through the stretch, a code following track relay and a code following line relay each responsive to coded current, and said relays arranged to govern the operation of the signal, a current source adapted to supply coded current, and directional means to render the current source effective to supply coded current to either the track relay or to the line relay depending upon the direction of traffic.

7. In combination, a stretch of traffic rails over which traffic may move in either direction, a signal to govern traffic through the stretch, a decoding relay to control the signal, a code following track relay and a code following line relay associated with the decoding relay, decoding means to energize the decoding relay in response to code operation of either the associated track relay or line relay, a current source adapted to supply coded current, and directional means to render the said source effective to supply coded current to either the track relay or to the line relay depending upon the direction of travel.

8. In combination, a stretch of traffic rails over which traffic may move in either direction, a signal to govern traffic through the stretch, a decoding relay to control the signal, a code following track relay and a code following line relay associated with the decoding relay, decoding means to energize the decoding relay in response to code operation of either the associated track relay or line relay, a current source adapted to supply coded current, and directional means to render the said source effective to supply coded current to either the track relay or to the line relay depending upon the direction of travel.

travel and to place the decoding means under the control of the relay to which coded current is supplied.

9. In combination, a stretch of traffic rails over which traffic may move in either direction, a signal having several distinctive indications to govern traffic through the stretch, a plurality of decoding relays to selectively govern the several indications of the signal, a code following track relay and a code following line relay associated with said decoding relays, decoding means to selectively energize the decoding relays in accordance with the code operating either the associated track relay or the line relay, a current source adapted to supply coded current of different codes, means to render the source effective to supply coded current to either the track relay or to the line relay depending on the direction of traffic and to place the decoding means under the control of the relay to which coded current is supplied, and circuit means to select the different codes in accordance with traffic conditions in advance of the signal.

10. In combination, a stretch of traffic rails over which traffic may move in either direction, a signal having several distinctive indications to govern traffic through the stretch, a code following track relay and a code following line relay each responsive to coded current of different codes and arranged to selectively control the several indications of the signal according to different codes, a current source adapted to supply coded current of different codes, directional means to render the current source effective to supply coded current to either the track relay or to the line relay according to the direction of traffic, and circuit means to select the different codes in accordance with traffic conditions in advance of the signal.

11. In combination, a stretch of traffic rails over which traffic may move in either direction, a signal having several distinctive indications to govern traffic through the stretch, a plurality of decoding relays to selectively govern the several indications of the signal, a code following track relay, decoding means associated with the track relay to selectively energize the decoding relays according to the code operating the track relay, a current source adapted to supply coded current of different codes to the track relay, means to select the different codes according to traffic conditions in advance of the signal, and a traffic controlled directional control circuit to render the track relay effective to control the decoding means in response to traffic in one direction and to render said track relay ineffective to control the decoding means in response to traffic in the other direction.

12. In combination, a track section, a current source located at each end of the section

and each adapted to supply coded current to the traffic rails, a track relay located at each end of the section connected to the traffic rails and each responsive to coded current, a decoding relay associated with each track relay energized in response to code operations of its associated track relay, a traffic controlled directional control circuit, means controlled by said control circuit to render the current source at one end of the section effective to supply coded current and to render the track relay at the opposite end of the section effective to control its decoding relay in response to traffic in one direction and to render the other current source effective to supply coded current and the track relay opposite said other source effective to control its decoding relay in response to traffic in the other direction, and a signal controlled by each decoding relay.

13. In combination, a first and a second track section, a track circuit for each section, a source of current for each track circuit, coding means for coding the current supplied by the source to the track circuit of the first track section, a track relay for the track circuit of the first track section responsive to such coded current, a contact operated by said track relay and included in the track circuit for the second section to thereby reproduce the code of the first track circuit in the second track circuit, and a signal controlled by the second track circuit.

14. In combination, a first and a second track section, a source of alternating current for each section, each adapted to be connected across the traffic rails at the exit end of its respective section, coding means to code the alternating current supplied to the traffic rails of the first track section, a track relay connected across the traffic rails at the entrance end of the first section and responsive to such coded alternating current, a contact for said relay included in the connection between the source and the traffic rails of the second section to thereby reproduce the code of the first section in the second section, and a signal controlled by the coded alternating current flowing in the rails of the second section.

15. In combination, a first and a second track section over which traffic may move in either direction, means for supplying coded current of different codes to the rails of each section, a track relay for each section responsive to such coded current in the rails, a directional means, means rendered effective by the directional means in response to traffic in one direction to repeat the code operating the track relay of the first section in the current supplied to the traffic rails of the second section, and other means rendered effective by the directional means in response to traffic in the other direction to select the code to be supplied to the rails of the first sec-

tion in accordance to the traffic conditions of the second section.

16. In combination, a first and a second track section, a signal located at the adjacent ends of the track sections to govern traffic traveling from the first to the second section, a current source to supply coded alternating current of different codes to the traffic rails of each track section; directional means responsive to traffic traveling in the direction opposite that governed by the signal to render the current source effective to supply to the rails of the second section under all traffic conditions alternating current of the same code as that operating the track relay of the first section, and said directional means responsive to traffic in the same direction as that governed by the signal to render the current source effective to supply to the rails of the first section alternating current of a code selectively governed by traffic conditions in advance of the signal.

17. In combination, a first and a second track section, means adapted to supply coded alternating current to the traffic rails of each section, traffic controlled means to repeat the code supplied by said means to the rails of the first section in the current supplied to the rails of the second section in response to traffic in one direction and to repeat the code supplied by said means to the rails of the second section in the current supplied to the rails of the first section in response to traffic in the opposite direction, and signals controlled by the coded alternating current supplied to the traffic rails of said sections.

18. An absolute permissive block signaling system including, traffic rails arranged in track sections, a first and a second current source for each section located at opposite ends of the sections and each adapted to supply coded alternating current, a code following track relay located at each end of each section, a code following line relay for each section and located at one end of the section; a directional line circuit for each section responsive to traffic in one direction to render the first current source effective to supply coded current to the two track relays of the section and the second current source effective to supply coded current to the line relay of the section, and said directional circuit responsive to traffic in the other direction to render the first current source ineffective and the second source ineffective to supply current to the line relay but effective to supply current to the two track relays of the section, and signaling means controlled by said track relays and said line relays.

19. An absolute permissive block signaling system including, a stretch of single track railway arranged in track sections, an eastbound signal and a westbound signal for each section, a first and a second code following track relay for each section located at opposite

ends of the section and arranged with the first relay normally controlling the eastbound signal of the section, a code following line relay for each section normally controlling the westbound signal of the section, a directional control circuit for each section responsive to an eastbound train entering the stretch to render the line relay of each section ineffective to control its signal, and said directional control circuit responsive to a westbound train entering the stretch to render the first track relay of each section ineffective to control its signal and to transfer the control of the westbound signal from the line relay to the second track relay of the section, and traffic controlled means to supply coded current to the two track relays and to the code following line relay of each section.

20. An absolute permissive block signaling system including, a plurality of track sections, a first and a second current source for each section located at opposite ends of the sections and each adapted to supply coded alternating current, a code following track relay located at each end of each track section, a code following line relay for each section and located at one end of the section; directionally controlled means for each section under the joint control of the track relays and said line relay of the section to render the first source normally effective to supply coded current to the track at one end and render effective the second source to supply current to the other end when a train moves toward said other end, and means controlled by a train to render ineffective a source to supply coded current ahead of an opposing train.

21. An absolute permissive block signaling system including, a first and a second track section, a first and a second current source for each section located at opposite ends of the section and each adapted to supply coded alternating current to the section, a normally closed directional line circuit for the first section opened by traffic entering said first section in one direction, a normally closed directional line circuit for the second section opened by traffic entering said second section in one direction and by opening the directional line circuit of said first section, and means controlled by said directional line circuits for removing the source of coded current of said second section nearest the train.

22. An absolute permissive block signaling system including, a first and a second track section, a first and a second current source for each section located at opposite ends of the section and each adapted to supply coded alternating current to the section, a normally closed directional line circuit for the first section opened by traffic entering said first section in one direction, a normally closed directional line circuit for the second section opened by traffic entering said second section in one direction and by open-

ing the directional line circuit of said first section, means controlled by said directional line circuits for removing the source of coded current of said second section nearest the train and for applying the source of coded current at the farthest end of said second section.

23. A stretch of single track railroad including, a plurality of signals for governing train moments in each direction, track sections, means for supplying coded current to the east end of each track section, a track relay at the west end of each track section responsive to the code delivered to the east end, a line circuit for each track section, means for supplying coded current to said line circuit at the west end, a line relay at the east end of each section responsive to the code delivered to the line circuit, means for normally governing eastbound signals by said track relays and for governing westbound signals by said line relays, and means for depriving said track circuits of coded current if a train enters the stretch from the east and for depriving said line circuits of coded current if a train enters said stretch from the west.

24. A stretch of single track railroad including, a plurality of signals for governing train movements in each direction, track sections, means for supplying coded current to the east end of each track section, a track relay at the west end of each track section responsive to the code delivered to the east end, a line circuit for each track section, means for supplying coded current to said line circuit at the west end, a line relay at the east end responsive to the code delivered to the line circuit, means for normally governing said westbound signals by track relays and for governing westbound signals by said line relay, and directional means for governing said westbound signals by track relays and for deenergizing said line relays.

45 25. A stretch of single track railroad arranged in track sections, a directional line circuit for each section, a source at the east end of each section to normally supply current to the directional line circuit of the section, means responsive to a train entering a section at the east end to disconnect the source from the directional line circuit of the section, means responsive to an eastbound train to disconnect the source at the east end from the directional line circuit and to connect a source at the west end of the section to the directional line circuit, and signals to govern traffic in opposite directions controlled by said directional line circuit.

26. A stretch of single track railroad arranged in track sections, a directional line circuit for each section including a line relay at each end of the section, a source of current, a source at the east end of each section

to normally supply current to the directional line circuit of the section, means responsive to a train entering a section at the east end to disconnect the source from the directional line circuit of the section, means responsive to an eastbound train entering the section to disconnect the source at the east end from the directional line circuit and to connect a source at the west end of the section to the directional line circuit, and signals to govern traffic in opposite directions controlled by the said line relays.

27. A stretch of single track railroad arranged in track sections, a first line circuit for each section, a source at the west end of each section to normally supply the said line circuit with coded current, a line relay at the east end of each track section connected to the line circuit and responsive to such coded current, a directional line circuit for each section, a source at the east end of each section to normally supply current to said directional line circuit; means responsive to an eastbound train to disconnect the source of coded current from the first line circuit and to connect a source of current, and to disconnect the source of current at the east end of the section from the directional line circuit and to connect the directional line circuit to the first line circuit of the section; a westbound signal controlled by said line relay and an eastbound signal controlled by said directional line circuit.

In testimony whereof I affix my signature.

HERBERT A. WALLACE.
